W. A. SMITH

WATER AND AIR TUBE CONNECTION

Filed Aug. 26, 1926

INVENTOR
William A. Smith.
BY Robert G. Odell
HIS ATTORNEY.

UNITED STATES PATENT OFFICE.

WILLIAM A. SMITH, OF SAYRE, PENNSYLVANIA, ASSIGNOR TO INGERSOLL-RAND COMPANY, OF JERSEY CITY, NEW JERSEY, A CORPORATION OF NEW JERSEY.

WATER AND AIR TUBE CONNECTION.

Application filed August 26, 1926. Serial No. 131,731.

This invention relates to rock drills, but more particularly to a water and air tube connection for fluid actuated rock drills of the hammer type.

5 The objects of the invention are to securely hold a pair of fluid conveying tubes in a rock drill, to prevent leakage of fluid from the back head into the cylinder, and to simplify the construction and operation of devices of this character.

10 Other objects will be in part pointed out and in part obvious.

The invention consists of the combination of elements and arrangement of parts substantially as hereinafter described and more particularly pointed out in the appended claims and illustrated in the accompanying drawings, in which

15 Figure 1 is a longitudinal sectional elevation of a rock drill equipped with a connection constructed in accordance with the practice of the invention,

20 Figure 2 is an enlarged detail sectional view of the back head illustrating the channels through which pressure fluid is conveyed to the outer or air tube, and

25 Figure 3 is a view similar to Figure 2 illustrating the channels through which water is conveyed from a source of supply to an inner or water tube.

30 Referring to the drawings, the invention is embodied in a rock drill in which a cylinder A, a front head B, and a back head C comprise the casing of the drill and are held in assembled position with respect to each other by the usual side bolts (not shown). A front cylinder washer D acts as a closure for the front end of the cylinder A and is bored to receive slidably a fluted 35 extension E of a hammer piston F reciprocable in the cylinder A.

35 Arranged in the front end of the front head B is a chuck jaw G having flats H which cooperate with wings J of a hollow drill steel K for preventing relative rotation between the jaw and the drill steel. At the rearward end of the chuck G are formed clutch members L of a well known type which interlock with similar clutch members 40 O formed on the forward end of a chuck

P. A chuck bushing Q carried by the chuck P holds the drill steel K centrally within the front head, and also acts as an abutment for the wings J to limit inward movement of the drill steel in the front head. The chuck 55 P is in this instance interlocked with the fluted extension E of the piston F by means of a chuck nut R screwed into the rearward end of the chuck P.

Means are provided for rotating the drill 60 steel in the drill hole. Such means consist in the present instance of a rifle bar S which

engages the piston F in the usual manner and carries at its rearward end a head T in which are arranged suitable pawl devices U. 65 The pawls U are preferably of a type which are adapted to be forced outwardly by suitable spring pressed plungers (not shown) to engage teeth V of a ratchet ring W for holding the rifle bar S stationary during the 70 rearward stroke of the piston. In this way the piston and the drill steel, together with the associated interlocking parts, may rotate a partial revolution to change the position of the drill steel in the drill hole. The 75

pawl U are so positioned in the head T that during the forward stroke of the piston, or in other words, the delivery stroke, the rifle bar will be free to rotate with the piston. In this instance the rifle bar extends through 80 a bore X of a back cylinder washer Y which acts as a closure for the rearward end of the cylinder.

Pressure fluid for actuating the drill is conveyed to a valve chest Z through a connection 85 b and the admission of such pressure fluid into the valve chest is controlled by a throttle valve c provided with a lever d whereby the said throttle valve may be manipulated. Any suitable type of valve (not shown) may 90 be arranged in the valve chest Z for controlling the distribution of pressure fluid to the cylinder A.

To the end that a constant supply of 95 cleansing fluid, such as water, may be conveyed to the drill steel K for flushing or cleansing the drill hole, a pair of tubes e and f are arranged concentrically with respect to each other and extend through the cylinder A with their forward ends and with 100

their rearward ends into the back head C. The inner or water tube *f* is preferably of sufficient length to permit its front end to extend within the drill steel K and the outer tube *e* is preferably only of a length to extend with its front end slightly rearwardly of the drill steel K when the said drill steel is in its rearwardmost limiting position.

Near the rearward end of the tube *e* is formed a bulb *g* which is seated in a tapered bore *h* in the back head C to form a fluid tight joint for preventing leakage of fluid from a recess *j* in the back head C into the cylinder A. The recess *j* is preferably threaded throughout a portion of its length as at *k* to receive a water plug *o* which bears with its front end on the bulb *g* for pressing the said bulb to its seat. The rearward end of the tube *e* is preferably extended into the water plug *o* and is in constant communication with a recess *p* in the water plug *o*, communicating with the recess *j* through longitudinal passages *q* in the forward or inner portion of the water plug *o*.

Suitable channels are provided for conveying pressure fluid from the throttle valve to the recess *j*. To this end a passage *r* is formed in the back head C to communicate at one end with the inner end of the recess *j* and at its other end with a ferrule *s* interposed between the back head and the cylinder, said ferrule forming a continuation of the passage *r* and registering with a passage *t* in the cylinder and the valve chest and leading to the throttle valve *c*. The passage *t* is preferably so positioned with respect to the throttle valve that when pressure fluid is being admitted to the distributing valve a constant supply of pressure fluid will be simultaneously supplied to the tube *e* during the reciprocation of the piston.

The tube *f*, like the tube *e*, is also provided with a bulb *u* near its rearward end which cooperates with a tapered bore *v* in the water plug *o* for preventing leakage of water between the bulb and the water plug. A convenient means for holding the bulb *u* on its seat is provided in the form of a plug *w* which is screwed into the rearward end of the water plug *o* to bear against the bulb *u*. A cap *x* screwed on the end of the water plug *o* serves to lock said water plug firmly in position and is adapted to bear on the back head C for sealing the recess *j*. If desired, a gasket *y* may be interposed between the cap *x* and the back head to seal the recess *j*.

Cleansing water is in this instance conveyed to the back head through a connection *z*, and such water may then pass through a passage 2 in the back head, through a longitudinal groove 3 in the water plug *o* and through an aperture 4 in the plug *w*. The aperture 4 is preferably of smaller diameter than the bore of the tube *f* to control the

amount of water admitted to the said tube.

In the operation of the device, whenever the throttle valve *c* is moved to the position for admitting pressure fluid to the distributing valve, pressure fluid will be simultaneously admitted to the passage *t* from whence it will flow through the ferrule *s*, the passage *r*, into the recess *j* and through the passages *q* and the recess *p* into the tube *e*. At the same time the valve or other means whereby the supply of water to the drill is controlled may be opened, and the water will then flow through the passages connecting the connection *z* with the water tube *f* and thence through the tube into the drill steel. In this way an adequate supply of cleansing liquid may be at all times supplied to the drill hole under sufficient pressure to remove any accumulated cuttings from the said drill hole. This is a desirable feature in devices of this character since water under sufficient pressure to remove the cuttings is not at all times available.

I claim:

1. In a rock drill, the combination of a cylinder, a back head for the cylinder having a recess constantly exposed to pressure fluid at its inner end, a pair of concentrically arranged fluid conveying tubes extending through the cylinder and the recess, bulbs on said tubes, a seat in the back head for the bulb on the outer tube, a water plug in the recess for holding the bulb of the outer tube firmly on its seat, said water plug having passages for conveying pressure fluid from the inner end of the recess into the outer tube, a seat in the water plug for the bulb on the inner tube, and a plug in the water plug for holding the bulb on the inner tube in fluid tight contact with its seat.

2. In a rock drill, the combination of a cylinder, a back head for the cylinder, a pair of concentrically arranged fluid conveying tubes extending through the cylinder, bulbs on said tubes, a conical seat in the back head for the bulb on the outer tube, a water plug in the back head for holding the bulb on the outer tube in fluid tight contact with its seat and for holding the tubes concentrically with respect to each other, said water plug having passages for conveying pressure fluid into the outer tube, a conical seat in the rearward end of the water plug for the bulb on the inner tube, and a plug in the rearward end of the water plug for holding the bulb on the inner tube in fluid tight contact with its seat.

3. In a rock drill, the combination of a cylinder, a back head for the cylinder having a recess, a pair of concentrically arranged fluid conveying tubes extending through the cylinder and a recess, bulbs on said tubes, a water plug in the recess bearing with its front end of the bulb of the outer tube to

form a fluid tight contact between the back head and the said bulb, said water plug having longitudinal passages in its front end conveying pressure fluid from the inner end of the recess to the outer tube, a seat in the rearward end of the water plug cooperating with the bulb on the inner tube for prevent-

ing leakage of fluid from one tube to the other, and a plug screwed in the water plug for holding the bulb on the inner tube firmly 10 on its seat.

In testimony whereof I have signed this specification.

WILLIAM A. SMITH.
